UNITED STATES PATENT OFFICE.

HENRY CHEVOLA, JR., OF NEW YORK, N. Y.

WINDOW-SASH LOCK.

1,049,671.

Specification of Letters Patent.

Patented Jan. 7, 1913.

Application filed September 27, 1911. Serial No. 651,560.

To all whom it may concern:

Be it known that I, HENRY CHEVOLA, Jr., a citizen of the United States, and residing at New York, in the county of New York and State of New York, have invented certain new and useful Improvements in Window-Sash Locks, of which the following is a specification, such as will enable those skilled in the art to which it appertains to make and use the same.

This invention relates to window sash locks, and particularly to locks of this class adapted to be applied to vertically movable sashes, the sashes being divided centrally and vertically into two separate parts which are hinged at the sides of the window frame and adapted to swing inwardly to facilitate the cleaning thereof, and for other purposes; and the object of the invention is to provide sash locks of the class specified which can only be manipulated when the sashes are in an open position, or when the top sash is lowered and the bottom sash raised; and with this and other objects in view the invention consists in sash locks of the class specified constructed and operating as hereinafter described and claimed.

The invention is fully disclosed in the following specification, of which the accompanying drawing forms a part, in which the separate parts of my invention are designated by suitable reference characters in each of the views, and in which;—

Figure 1 is an inside view of a window having sashes constructed in the manner set out, and provided with my improved lock;—Fig. 2 a transverse section on the line 2—2 of Fig. 1, and on an enlarged scale and indicating the sashes open in dotted lines;—Fig. 3 a section on the line 3—3 of Fig. 2, and on an enlarged scale;—Fig. 4 a section on the line 4—4 of Fig. 3, and Fig. 5 a section on the line 5—5 of Fig. 3.

In the drawing forming part of this specification, and for the purpose of showing the construction and operation of my improved sash locks, I have shown at *a* a window frame comprising the usual side members *a*² and top and bottom members *a*³ and *a*⁴, and in which are mounted the usual top sash *b* and bottom sash *c*. The sides of the frame are provided with the usual counterbalance weight chambers in which are placed the usual counterbalance weights *e*, and the sashes are supported by the usual counterbalance cords *f* connected with said

weights and with vertically movable strips *g* at the opposite sides of the frame, and the sashes *b* and *c* are divided centrally and vertically into separate similar parts *b*² and *c*² which are hinged to the strips *g*, all this construction being well known and forming no part of my invention.

The back part of the window frame in which the top sash *b* is mounted is narrower than the front part, as clearly indicated in Fig. 2, and with this construction the separate sash members may be freely opened, as indicated in dotted lines in Fig. 2, and this construction is also well known and forms no part of my invention.

The separate parts of the outer or top sash *b* and the separate parts of the inner or bottom sash *c* are provided both at the top and bottom thereof with locking devices *i* whereby they may be locked together and thus made to operate as a single sash when desired, or whereby they may be separated and swung inwardly as indicated in Fig. 2 for the purpose of cleaning said members or for the purpose of ventilation, but it will be understood that the parts of the top sash cannot be swung inwardly except when the parts of the bottom sash are similarly manipulated, and the top and bottom sashes are also provided at *l* with an ordinary sash lock whereby the vertical movement thereof may be prevented, or said sashes may be locked in a closed position in the usual manner and the lock *l* may be of any preferred construction, and may be locked in any desired position.

The construction of the sash locking device or devices *i* is clearly shown in Figs. 2, 3, 4 and 5, and in this construction I employ two L-shaped plates *j* and *k* the longer arms of which are countersunk in the top and bottom of the separate sash members and the shorter arms of which are countersunk in the adjacent faces of said separate members, and said plates are secured in position by screws *m*. The plate *j* is provided in the angle portion thereof with a longitudinal bed member *j*² at the inner end of which is a push-button *j*³ having an inwardly directed knob *j*⁴ and secured at *j*⁵ is a spring arm *j*⁶ which ranges longitudinally of the plate *j* and which is adapted to bear on the knob *j*⁴ and which is also provided at its free end with a stop pin *j*⁷, and secured to the plate *j* in the angle portion thereof or adjacent thereto is a keeper *j*⁸ having a

tongue portion j^9 which overlaps the free end of the spring arm j^6 and is adapted to limit the movement thereof. The plate k is provided with a central longitudinal and 5 countersunk slot or opening k^2 between which and the angle portion of said plate is a bed plate k^3 , and said plate k is also provided with a keeper k^4 similar to the keeper j^8 , and employed in connection with the 10 plates j and k and the parts connected therewith as above described is a lock bolt n which is freely movable through the keepers j^8 and k^4 and one end portion of which is provided with a triangular head n^2 having 15 a neck portion n^3 which passes through the slot or opening k^2 and the other end portion of the bar n is provided with an aperture n^4 adapted to receive the stop pin j^7 of the spring arm j^6 , and secured in the keeper k^4 20 is a spring o which bears on the bolt n and regulates the movement thereof, and said bolt is adapted to be operated or moved longitudinally by means of the head n^2 thereof and is freely movable through apertures p in the shorter arm portions of the L-shaped plates j and k .

In Fig. 3 of the drawing, one of the locking devices i is shown in operative position so as to secure the separate parts of one of 30 the sashes together at the top thereof, and in order to unlock the sash members, the push-button j^3 is forced inwardly. This forces the corresponding arm j^6 inwardly and releases the bolt n and said bolt may be 35 moved to the right by means of the head n^2 thereof until it is entirely withdrawn from the plate k and the sash member with which said plate is connected and the separate sash members may be swung inwardly as will be 40 readily understood. When it is desired to lock the said sash members together they are swung back or outwardly into the position shown in Figs. 1, 2 and 3, and the bolt n is forced to the left by means of the head 45 n^2 thereof. The end of the bolt n in which the aperture n^4 is formed is beveled as shown at n^5 and in the above described operation said beveled end passes under the stop

pin n^4 and forces the spring arm j^6 downwardly or inwardly as shown in dotted lines 50 in Fig. 3 until the bolt reaches the position shown in said figure, in which position the arm j^6 operates automatically to secure said bolt, and the sash members are locked together. It will be understood that this operation is exactly the same both at the top and bottom of the separate sash members of each of the sashes.

From the foregoing description it will be seen that I accomplish the object of my invention as hereinbefore set out by means of a simple, effective and comparatively inexpensive construction and in which changes and modifications may be made, within the scope of the appended claim, without departing from the spirit of my invention or sacrificing its advantages.

Having fully described my invention, what I claim as new and desire to secure by Letters Patent, is:—

In a sash lock, two L-shaped plates, the longer parts of which are provided on the inner sides thereof in the angles thereof with bed members, a bolt movable longitudinally on said bed members and through the shorter parts of said L-shaped plates, means for operating said bolt through the longer part of one of said plates, the longer part of the other plate being provided with a push button movable therethrough, and with a 75 spring arm which extends over said button, and bears thereon, and over said bolt, said spring arm being provided with a projection and said bolt with an aperture adapted to receive said projection, and the longer 80 parts of said plates being provided with keepers through which said bolt passes.

In testimony that I claim the foregoing as my invention I have signed my name in presence of the subscribing witnesses this 90 25th day of September 1911.

HENRY CHEVOLA, JR.
